UNITED STATES PATENT OFFICE.

FELIPE GIROUD, DECEASED, LATE OF NEW YORK, N. Y., BY EDITH ELMIRA CHAPMAN,
EXECUTRIX, OF NEW YORK, N. Y., ASSIGNOR TO PACKAGE MACHINERY COMPANY,
OF SPRINGFIELD, MASSACHUSETTS, A CORPORATION OF MASSACHUSETTS.

WRAPPING-MACHINE.

1,129,975.

Specification of Letters Patent.

Patented Mar. 2, 1915.

Application filed August 19, 1914. Serial No. 857,529.

To all whom it may concern:

Be it known that FELIPE GIROUD, deceased, late a citizen of the Island of Cuba and a resident of the city of New York, in the county of New York and State of New York, did invent a certain new and useful Improvement in Wrapping-Machines, of which the following is a specification.

This invention relates to machines having means whereby an article and a wrapper can be forced through a wrapper folding channel whereby the wrapper is folded upon the article.

The object of the invention is to provide means whereby the article is effectually covered by the wrapper, and to provide means whereby the wrapper is secured to the article.

The invention consists of means whereby paste is applied to approximately all of one side of a wrapper, and conveying belts coöperating with a movable guide adapted to move the paste coated wrapper to rest between a wrapper folding channel and the article to be wrapped.

The invention also consists of swinging doors which are located between the article and the wrapper so that forward movement of the article causes the doors to be swung against the wrapper, whereby the wrapper is moved against the wrapper folding channel previous to the time the article reaches it. The wrapper folding channel is provided with brushes and rollers adapted to press the wrapper against the article during travel of the article and wrapper along said wrapper folding channel, whereby the paste coated wrapper is forced against the article, said paste then serving to hold the wrapper to the article.

The invention further consists of wrapper folding mechanisms having yielding arms carrying rollers which are adapted to fold and press certain portions of the paste coated wrapper against the article. A swinging folder is provided having two laterally pivoted thereto, said laterally pivoted folders being actuated by two reciprocating slides. These folders serve to fold the paste coated wrapper against the article, and also to partially fold certain unfolded paste coated portions of the wrapper. Pivoted to each of said reciprocating slides are two swinging folders, which

during forward movement of the slides, take against stationary inclined surfaces which cause the folders to be swung against said partial folds of the wrapper, causing said partial folds to be forced against stationary parts of the machine, whereby the paste coated portions of said folds are forced together. During return movement of said reciprocating slides, a part thereof takes against and moves auxiliary slides having inclined surfaces which further press and crease said folds of the wrapper.

In the accompanying drawings: Figure 1 is a side elevation of the machine. Fig. 2 is a perspective view of a wrapper having approximately all of one side thereof coated with paste or other adhesive substance. Fig. 3 is a perspective view showing said wrapper partially folded upon an article. Fig. 4 is a horizontal section on the line IV—IV of Fig. 1. Fig. 5 is a horizontal section on the line V—V of Fig. 1. Figs. 6 and 7 are perspective views showing folds of the wrapper succeeding those shown in Fig. 3. Fig. 8 is a cross section on the line VIII—VIII of Fig. 1. Fig. 9 is a cross section on the line IX—IX of Fig. 1. Fig. 10 is a fragmentary view similar to Fig. 9, showing a different position of the wrapper carrying and guiding plate. Fig. 11 is a cross section on the line XI—XI of Fig. 1. Fig. 12 is a longitudinal section on line XII—XII of Fig. 11. Fig. 13 is a perspective view showing folds of the wrapper succeeding those shown in Fig. 7. Fig. 14 is a horizontal section on the line XIV—XIV of Fig. 12. Fig. 15 is a fragmentary view similar to Fig. 14, showing parts moved to a different position. Fig. 16 is a sectional elevation on the line XVI—XVI of Fig. 15. Fig. 17 is a sectional elevation showing some of the parts shown in Fig. 12 moved to a different position. Figs. 18 and 19 are perspective views showing folds of the wrapper succeeding those shown in Fig. 13. Fig. 20 is a cross section on the line XX—XX of Fig. 17. Fig. 21 is a cross section on the line XXI—XXI of Fig. 17. Fig. 22 is a sectional view of a portion of the machine, showing the auxiliary slides having the inclined surfaces.

Journaled in suitable bearings in the main frame 1 of the machine is a driving shaft 2. Secured to driving shaft 2 is a bevel gear

wheel 3 in mesh with a bevel 4 which is secured to the lower end of a vertical shaft 5. To the upper end of vertical shaft 5 is secured a bevel gear wheel 6 in mesh with a bevel gear wheel 7 which is secured to a shaft 8, journaled in a pair of standards 9. To shaft 8 is secured a roller 10 having part of its surface traveling in contact with paste 11 in a receptacle 12 which is attached to the upper ends of standards 9. Secured to shaft 8 is a gear wheel 13 in mesh with a gear wheel 14 which is in mesh with a gear wheel 15. Gear wheel 15 is secured to a shaft 16 having a roller 17 secured thereto. 15 A portion 18 of the circumference of roller 17 is adapted to travel in contact with the paste on roller 10, whereby said paste is transferred from roller 10 to said portion 18 of roller 17. Roller 17 is provided with a 20 series of grooves 19 in which a corresponding series of endless belts or cords 20 and 21 are arranged to travel. From grooves 19 the belts 20 travel in contact with endless belts 22, thence down and around pulleys 23, thence up and over pulleys 24 back to grooves 19. From grooves 19 the belts 21 travel in contact with endless belts 25 down and around pulleys 26, thence up and over pulleys 27 back to grooves 19. A series of 25 cleaners 28 projecting into grooves 19 serve to remove paste previous to travel of said belts 20 and 21 back into said grooves.

Secured to shaft 16 is a gear wheel 29 which drives a series of gear wheels 30, 31 and 32. Gear wheel 32 is secured to a shaft 33 having pulleys 34 and 35 secured thereto. Pulleys 34 serve to drive belts 22, and pulleys 35 serve to drive belts 25. From pulleys 34 the belts 22 travel downward parallel to belts 20, over idle pulleys 36 and around pulleys 37, thence up over idle pulleys 38 back to pulleys 34. From pulleys 35 the belts 25 travel downward parallel to belts 21, over idle pulleys 39 and around pulleys 40, thence up over idle pulleys 41 back to pulleys 35.

Secured to shaft 33 is a gear wheel 42 which drives gear wheels 43 and 44. Gear wheel 44 is secured to a shaft 45 which is journaled in swinging arms 46. Secured to shaft 45 is a series of narrow wheels 47. By means of springs 48 connected to arms 46, the wheels 47 are lightly pressed toward the under side of roller 17. Upward movement of rollers is checked by means of an adjustable stop 49.

The grooves 19 in which the belts 20 and 21 travel, are made very narrow in order that the paste coated surface 18 of roller 17 may not be materially reduced in extent.

Secured to one end of the shaft 16 to which roller 17 is secured, is a crank arm 50 which is connected by a link 51 to a sliding carriage 52. The sliding carriage 52 actuates a paper feed mechanism 53 adapted during every

revolution of shaft 16 to feed a wrapper from a pile 54. As the paper feed mechanism forms no part of this invention further description thereof is not considered necessary.

Secured to vertical shaft 5 is a cam 55 adapted for engagement with a roller 56 journaled on a crank arm 57 which is secured to a rock-shaft 58. To rock-shaft 58 is secured an arm 59 which is connected by a link 60 to a plate 61 having vertical reciprocating movements on guides 62. The guides 62 are arranged to cause said movements of plate 61 to be across the entrance to a wrapper folding channel having an upper plate 63 and a lower plate 64. To link 60 is secured a shaft 65 upon which are journaled the idle pulleys 39 over which the endless belts 25 travel.

The cam 55 is shaped to cause movement of plate 61 upward to the position shown in Fig. 17, at the time the paper feed mechanism 53 has caused a wrapper 54 to be moved forward between the paste coated surface 18 of roller 17, and the series of wheels 47. Said upward movement of plate 61 is accompanied by upward movement of the idle rollers 39 thereby permitting movement of belts 25 away from the path of said upwardly moving plate.

Rotation of wheels 17 and 47 cause forward movement of the wrapper into engagement between the traveling belts 20, 22 and 21, 25, the paste coated surface 18 of roller 17 at the same time applying paste to approximately all of one side of the wrapper.

The traveling belts then carry the paste coated wrapper downward, until a portion of it passes the plate 61, at which time the plate and the rollers 39 will move downward, and as the plate 61 serves during this downward travel to hold the wrapper against downwardly moving portions of belts 20 and 21, the plate cooperating with the belts acts to move the wrapper downward as long as the downward movement of the plate continues. At the end of downward movement of the plate, the wrapper is brought to rest upon a support 66, the plate then serving to hold said wrapper across the entrance to said channel, as shown in Fig. 12.

Secured to shaft 2 is a cam 67 adapted for engagement with a roller 68 journaled on an arm of a bell crank lever 69 which is pivoted at 70 to the main frame. The other arm of lever 69 is connected to a cross-bar 71 having upwardly extending rods 72 at each end thereof. To the upper end of each rod 72 is secured a plate 73 upon which a series of articles 74 may be placed. The cam 67 is shaped to cause up and down movements of the articles 74 in vertical guides 75. An article in the lowered position as shown by dotted lines in Fig. 12 is in range with said wrapper folding channel, and rests

70

105

110

115

120

125

130

upon a support 76 located near the paste coated side of said wrapper. Between said article and the wrapper is a pair of pivoted doors 77, one of said doors extending vertically downward and the other extending vertically upward, said doors adapted to swing toward the upper and lower sides of the wrapper folding channel. Springs 78 serve to normally swing said doors to the vertical position.

Secured to driving shaft 2 is a bevel gear wheel 79 in mesh with a bevel gear wheel 80 which is secured to one end of a shaft 81. To the other end of shaft 81 is secured an arm 82 having at its free end a crank pin 83 upon which is journaled a roller 84. The roller 84 rides in a slot 85 formed in a lever 86 which is pivoted at 87 to the main frame. The free end of lever 86 is connected by links 88 to a plunger 89 having reciprocating movements in guides 90. Said reciprocating movements of plunger 89 are caused by rotation of shaft 81 carrying the arm 82 crank pin 83 and roller 84 traveling in the slot 85 formed in lever 86.

Forward movement of plunger 89 causes the article shown by dotted lines in Fig. 12 to be moved forward to the position shown in Fig. 16, during which movement the plate 61 will have moved upward, and said forward movement of the article will have caused said doors 77 to swing to the position shown in Fig. 16. Said swinging movement of the doors 77 cause them to take against the paste coated wrapper, and to hold it against the upper and lower sides of the wrapper folding channel at the time the upwardly moving plate 61 moves away from said channel. Then, as the article is moved forward by the plunger 89 the forward side of the article takes against the paste coated side of the wrapper, and the wrapper adhering to the article is forced between said upper and lower plates, thereby causing the paste coated side of said wrapper to be folded against the upper and lower sides of the article.

A portion 91 of the upper plate 63 of wrapper folding channel is made vertically movable and pressed downward by means of springs 92, thereby rendering easy the entrance of said wrapper and article into said wrapper folding channel. Mounted on each of said upper and lower plates is a brush 93 extending into said channel sufficient to exert a slight pressure on the portions of the wrapper folded against the upper and lower sides of the article. The brushing action caused by forward movement of the article and wrapper serves to make intimate contact of the paste coated side of the wrapper with the article. During said forward movement of the article and wrapper, the portions *a* of the wrapper projecting beyond

the sides of the article take against projections 94 extending into said channel from the two sides thereof, thereby causing the paste coated sides of said portions *a* to be folded against the sides of the article as shown in Fig. 3. The height of said inwardly extending side projections 94 is sufficient to make only partial folds of the paste coated sides of the triangular flaps *b* toward the paste coated sides of the flaps *c* extending beyond the upper and lower sides of the article. During further forward movement of said article and wrapper, said partial folds of triangular flaps *b* take against upper and lower inclined surfaces 95 formed on inwardly extending side projections 96 which extend nearer to said upper and lower plates than do the inwardly extending projections 94, thereby causing said partial folds to be pressed against said upper and lower plates, whereby the paste coated sides of said triangular flaps *b* are forced against the paste coated sides of the flaps *c*. During further forward movement of the article and wrapper, the portions *a* folded against the sides of the article take against rollers 97, the circumference of which travels nearer to said article than the projections 94 extend, whereby the paste coated sides of said portions *a* are firmly pressed against the article. Rollers 97 are journaled in projections 98 extending inward from the sides of the wrapper folding channel, each of said projections having upper and lower inclined surfaces 99, and having a recess 100 between the upper and lower sides thereof, for purposes hereinafter described.

Secured to vertical shaft 5 is a cam 101 adapted for engagement with a roller 102 journaled on a crank arm 103 which is secured to a rock-shaft 104. To rock-shaft 104 is secured an arm 105 which is connected by a link 106 to a plunger 107 having vertically reciprocating movements on guide rods 108. Springs 109 pressing against the under side of the plunger 107 and acting on link 106, arm 105, rock-shaft 104 and arm 103, serve to keep roller 102 in engagement with cam 101. Journaled in bearings on plunger 107 is a rock-shaft 110 having a downwardly extending arm 111 secured to each end thereof. Collars 112 are secured to the rock-shaft 110, and to each of said collars, one end of a coiled spring 113 is connected. The springs are coiled around shaft 110 and the ends of the springs brought into engagement with the plunger 107, whereby said springs cause swinging movement of the arms 111 toward a stop 114. Journaled in the lower ends of arms 111 is a roller 115 having a ratchet wheel 116 secured thereto. A spring pressed pawl 117 pivoted on an arm 111 and engaging said ratchet wheel, permits rotation of the roller in one direction and prevents it in the other direction.

Downward movement of plunger 107 causes roller 115 to take against the upper wrapper flap *d* overhanging the rear of the article, shown in Fig. 3, causing said flap to be turned downward, said springs 113 causing the roller 115 to press the paste coated side of the flap against the rear of the article, as shown in Figs. 6 and 17.

Secured to shaft 2 is a cam 118 adapted 10 for engagement with a roller 119 journaled on one arm of a bell-crank lever 120 which is pivoted at 121 to the main frame. The other arm of the lever 120 is provided with a slot 122 in which a pin 123 travels. Pin 15 123 is mounted on a plunger 124 having vertically reciprocating movements on guide rods 125. Forming part of plunger 124 are extensions 126 having slots 127 in which pins 128 travel. Pins 128 are secured to 20 swinging arms 129 which are pivoted at 130 to the main frame. Secured to the free ends of swinging arms 129 is an upwardly extending plate 131 having a laterally swinging plate 132 pivoted to each end thereof. 25 The two plates 132 are connected by a spring 133 which normally maintains said plates in alinement with said upwardly extending plate 131.

Upward movement of plunger 124 causes 30 upward movement of the swinging arms 129 carrying the upwardly extending plate 131, causing said upwardly extending plate to take against the lower wrapper flap *d* extending beyond the rear of the article, as 35 shown in Fig. 6, thereby causing said flap to be turned upward, the pivot of said swinging arms being arranged to cause said upwardly extending plate to press the paste coated side of said flap against the rear of the article and against the folded upper flap *d*, as shown in Figs. 7 and 12.

When the upwardly extending plate 131 has reached its uppermost position the laterally swinging plates 132 pivoted to the 45 ends thereof will be in range with side flaps *e* forming part of the folded rear flaps *d*, and also in range with projections 134 extending inward from slides 135 having reciprocating movements on dovetail guides 50 136 formed in the sides of said wrapper folding channel. Pivoted to each of the reciprocating slides 135 are upper and lower swinging arms 137 which are normally held against the extensions 134 by means of 55 springs 138.

One end of a link 139 is pivoted to each of the reciprocating slides 135, and the other end of each of said links is provided with a slot 140 in which a pin 141 travels. The 60 pins 141 form part of arms 142 which are secured to a rock-shaft 143. Secured to rock-shaft 143 is an arm 144 which is connected to a bar 145 having a slot 146 through which the shaft 81 passes. Journaled on a 65 pin 147 forming part of bar 145 is a roller

148 which travels in a cam groove 149 formed on a cam 150 which is secured to shaft 81. By means of the described intermediate connections the cam 150 causes reciprocating movements of slides 135. Forward movement of slides 135 cause the extensions 134 thereof to take against the pivoted plates 132, causing said plates to swing and thereby to fold the flaps *e* toward the sides of the article, the pivots of said plates 70 arranged to cause the paste coated side of said flaps to be pressed against said article, as shown in Figs. 13 and 14. The height of the pivoted plates 132 is sufficient to make only partial folds of the paste coated 80 sides of the triangular flaps *f* toward the paste coated sides of the flaps *e* extending beyond the upper and lower sides of the article. The slides 135 during further forward movement thereof take against an auxiliary 85 slide 151, and move said auxiliary slide from the position shown in Fig. 15 to the position shown in Fig. 14. The inclined surfaces 95 previously referred to are formed on the upper and lower extensions 96 of the 90 auxiliary slides 151. The space 152 between the upper and lower extensions 96 is sufficient to permit said extensions to travel clear of the inwardly extending projections 98 carrying the rollers 97. The recesses 100 95 in projections 98 previously referred to, permit said movement of the slides 135. Said forward movement of the slides 135 also cause said upper and lower arms 137 pivoted thereto to take against the upper 100 and lower inclined surfaces 99 on the projections 98, causing said arms to swing and thereby to force said partial folds of the triangular flaps *f* against the paste coated 105 sides of the flaps *e*; the pivots of said arms 137 arranged to cause said partial folds to be pressed against said upper and lower plates of the wrapper folding channel.

Return movement of the slides 135 permits return movement of the arms 137 pivoted thereto, and also permits return movements of the laterally swinging plates 132. Secured to each slide 135 is a rod 153 having a collar 154 secured thereto, so that as the slides 135 continue their return movement, 110 said collars 154 take against the auxiliary slides 151, causing the auxiliary slides to be moved from the position shown in Fig. 14 to the position shown in Fig. 15. The auxiliary slides are provided with flanges 115 155 which take against the standards 9 and thereby limit the return movement of said auxiliary slides. During said return movement of the auxiliary slides the inclined surfaces 95 on the upper and lower extensions 120 96 thereof take against said folds of the triangular flaps *f*, thereby forcing said folds tightly against said upper and lower plates, whereby said folds are firmly creased.

When the plunger 89 forces another ar- 130

ticle and wrapper into the wrapper folding channel, the preceding partially wrapped article having the unfolded wrapper flaps shown in Fig. 13 will be moved forward 5 along said channel by means of the succeeding article and wrapper. During said movement of the preceding partially wrapped article, the folded flaps *e* will travel against the rollers 97 which will cause said flaps to 10 be firmly pressed against the article.

In range with the upper unfolded wrapper flaps of the preceding article are rollers 156 which are journaled in swinging arms 157 mounted on the vertically reciprocating 15 plunger 107 in a manner similar to that in which the swinging arms 111 carrying the roller 115 are mounted. Downward movement of plunger 107 causes the rollers 156 to take against the upper unfolded wrapper 20 flaps of the preceding article, causing said flaps to be turned downward, action of the springs 113 causing the rollers 156 to press the paste coated sides of the flaps against the sides of the partially wrapped article, 25 as shown in Fig. 17.

In range with the lower unfolded wrapper flaps of the preceding article are rollers 158 which are journaled in upwardly extending swinging arms 159 which are 30 mounted on the vertically reciprocating plunger 124 in a manner similar to that in which the swinging arms 157 carrying the rollers 156 are mounted. Upward movement of the plunger 124 causes the rollers 35 158 to take against the lower unfolded wrapper flaps of the preceding article; causing said flaps to be turned upward; action of the springs 113 causing the rollers 158 to press the paste coated sides of the flaps 40 against the sides of the article, and against the folded upper flaps, causing the wrapper of the preceding article to be completely folded, as shown in Figs. 12 and 19.

As the preceding wrapped articles are 45 successively moved forward by means of succeeding partially wrapped articles, the wrapped articles are moved into a receiving channel 160, the sides of which are provided with endless traveling belts 161 which 50 serve to press the folded flaps against the sides of the articles, while permitting easy travel of the wrapped articles along said receiving channel.

Having described the invention, what I 55 claim is:

1. A wrapping machine comprising a wrapper folding channel, a support for a wrapper, endless traveling belts, a plate adapted for reciprocating movement parallel to certain of said traveling belts, wrapper feeding mechanism, a paste applying device located between said wrapper feeding mechanism and said traveling belts, 60 said wrapper feeding mechanism adapted 65 to feed a wrapper into range with said

paste applying device, and also to feed said wrapper coated with paste forward between said traveling belts, said belts adapted to move said paste coated wrapper forward between said traveling belts and said plate, 70 means for moving said plate in the same direction the belts are moving, whereby said paste coated wrapper is moved to rest on said wrapper support, means whereby an article can be forced against the paste coated 75 side of said wrapper; and means whereby said article and wrapper can be moved into said wrapper folding channel, whereby the paste coated side of said wrapper is folded upon the article, substantially as described. 80

2. A wrapping machine comprising a wrapper folding channel, a support for a wrapper, endless traveling belts, a plate adapted for reciprocating movement parallel to certain of said traveling belts, means 85 whereby paste can be applied to approximately all of one side of a wrapper; means for feeding said paste coated wrapper forward between said traveling belts, said belts adapted to move said paste coated 90 wrapper forward between said traveling belts and said plate; means for moving said plate in the same direction the belts are moving, whereby said paste coated wrapper is moved to rest on said wrapper support; means whereby an article can be forced against the paste coated side of said 95 wrapper; and means whereby said article and wrapper can be moved into said wrapper folding channel, whereby the paste coated 100 side of said wrapper is folded upon the article.

3. A wrapping machine comprising a wrapper folding channel, a support for a wrapper, endless traveling belts, a plate 105 adapted for reciprocating movement parallel to certain of said traveling belts, means whereby paste can be applied to approximately all of one side of a wrapper; means for feeding said paste coated wrapper forward between said traveling belts, said belts adapted to move said paste coated wrapper forward between said traveling belts and said plate; means for moving said plate in 110 the same direction the belts are moving, whereby said paste coated wrapper is moved to rest on said wrapper support, said plate then serving to hold said wrapper across the entrance to said wrapper folding channel, means whereby an article can be forced 115 against the paste coated side of said wrapper; means whereby said plate is moved away from the entrance to said wrapper folding channel; and means whereby said article and wrapper can be moved into said 120 wrapper folding channel, whereby the paste coated side of said wrapper is folded upon the article.

4. A wrapping machine comprising a 125 wrapper folding channel, a support for a 130

wrapper, endless traveling belts, a plate adapted for reciprocating movement parallel to certain of said traveling belts, wrapper feeding mechanism, a paste applying device located between said wrapper feeding mechanism and said traveling belts, said wrapper feeding mechanism adapted to feed a wrapper into range with said paste applying device, and also to feed said wrapper 10 coated with paste forward between said traveling belts, said belts adapted to move said paste coated wrapper forward between said traveling belts and said plate, means for moving said plate in the same direction 15 the belts are moving, whereby said paste coated wrapper is moved to rest on said wrapper support, said plate then serving to hold said wrapper across the entrance to said wrapper folding channel, means whereby 20 by an article can be forced against the paste coated side of said wrapper; means whereby said plate is moved away from the entrance to said channel; and means whereby said article and wrapper can be moved into 25 said wrapper folding channel, whereby the paste coated side of said wrapper is folded upon the article.

5. A wrapping machine comprising a wrapper folding channel, a reciprocating 30 plunger, a support for an article between said wrapper folding channel and said plunger, and a support for a wrapper between said wrapper folding channel and said article; endless traveling belts; a plate 35 adapted for reciprocating movement parallel to certain of said traveling belts; means whereby paste can be applied to approximately all of one side of a wrapper; means for feeding said paste coated wrapper forward 40 between said traveling belts, said belts adapted to move said paste coated wrapper between said traveling belts and said plate; means for moving said plate in the same direction the belts are moving, whereby said 45 paste coated wrapper is moved to rest on said wrapper support; said plate then serving to hold said wrapper across the entrance to said wrapper folding channel; upper and lower swinging doors extending vertically 50 between said article and said wrapper; means for actuating said plunger, whereby forward movement thereof forces said article against said doors, thereby causing said doors to swing against said wrapper; 55 and means whereby said plate is moved away from the entrance to said channel; further forward movement of said plunger then causing said article and wrapper to be forced into said wrapper folding channel, 60 whereby portions of said paste coated wrapper are folded upon the article.

6. A wrapping machine comprising a wrapper folding channel, a reciprocating plunger, a support for an article between 65 said wrapper folding channel and said

plunger, and a support for a wrapper between said wrapper folding channel and said article; means whereby paste can be applied to approximately all of one side of a wrapper, traveling belts adapted to move 70 said paste coated wrapper to rest on said wrapper support in such a manner that the paste coated side of said wrapper faces toward said article; a reciprocating plate between said wrapper and said channel, said plate serving to guide and hold said wrapper across the entrance to said channel; means whereby said reciprocating plate is moved from across the entrance to said channel; and means for actuating said 75 plunger, whereby forward movement thereof forces said article against said paste coated side of the article, further forward movement of said plunger causing said article and wrapper to be forced into said 80 wrapper folding channel, whereby portions of said paste coated wrapper are folded upon the article.

7. A wrapping machine comprising a wrapper folding channel having upper and lower plates, a reciprocating plunger, a support for an article between said wrapper folding channel and said plunger, and a support for a wrapper between said wrapper folding channel and said article; means whereby paste can be applied to approximately all of one side of a wrapper; traveling belts adapted to move said paste coated wrapper to rest on said wrapper support in such a manner that the paste coated side of 90 said wrapper faces toward said article; a vertically reciprocating plate between said wrapper and said channel, said plate serving to guide and hold said wrapper across the entrance to said channel; upper and lower 95 swinging doors extending vertically between said article and said wrapper; means for actuating said plunger, whereby forward movement thereof forces said article against said doors, thereby causing said doors to swing toward said wrapper; and means whereby said vertically reciprocating plate is moved from across the entrance to said channel; said swinging doors arranged to force said wrapper against said upper and 100 lower plates of the wrapper folding channel; further forward movement of said plunger then causing said article to be forced against said paste coated side of the wrapper, and causing said article and wrapper to 105 be forced into said wrapper folding channel, whereby portions of said paste coated wrapper are folded upon the article.

8. A wrapping machine comprising a wrapper folding channel, a support for a 110 wrapper and a support for an article; means whereby paste can be applied to approximately all of one side of a wrapper, and means for moving said paste coated wrapper to rest on said support in such a manner that 115

the paste coated side of said wrapper faces toward said article; means whereby said article and wrapper can be moved into said wrapper folding channel, whereby portions 5 of said paste coated side of said wrapper are folded upon the article, said folded portions of the wrapper having upper and lower unfolded paste coated flaps extending beyond the rear of the article; in 10 combination with upper and lower movable folders, said upper and lower unfolded flaps being in range with said folders; means for actuating said folders whereby said paste coated flaps are folded, 15 said folders arranged to swing toward the rear of said article, whereby said paste coated flaps are pressed against the rear of said article, substantially as described.

9. A wrapping machine comprising a 20 wrapper folding channel having upper and lower plates, a reciprocating plunger, a support for an article between said wrapper folding channel and said plunger, means whereby paste can be applied to approximately all of one side of a wrapper, means whereby said paste coated wrapper can be moved to rest between said wrapper folding channel and said article in such a manner 25 that the paste coated side of said wrapper faces toward said article, and means for actuating said plunger, whereby forward movement thereof forces said article against said paste coated side of the wrapper, further forward movement of said plunger 30 causing said article and wrapper to be forced into said wrapper folding channel, whereby portions of said paste coated wrapper are folded upon the article, said folded portions of the wrapper having upper and lower unfolded 35 paste coated flaps extending beyond the rear of the article; in combination with upper and lower movable folders adapted to fold and press said upper and lower paste coated flaps against the rear of said article; 40 one of said movable folders being provided with laterally swinging folders, reciprocating slides to the rear of and in range with said laterally swinging folders at the time the movable folder carrying said laterally 45 swinging folders has reached the end of its movement causing said folding and pressing of said paste coated flaps against the rear of said article, certain unfolded paste coated 50 portions of said folded flaps being at such times in range with said laterally swinging folders; and means for actuating said slides whereby forward movement thereof causes said laterally swinging folders to fold said unfolded paste coated portions of said folded 55 flaps, said laterally swinging folders arranged to cause said paste coated portions to be pressed against the sides of said article.

10. A wrapping machine comprising a 60 wrapper folding channel having upper and lower plates and inwardly extending side

projections; arms extending inward from the sides of said channel, said arms extending nearer to said upper and lower plates than do said inwardly extending side projections, and said arms having upper and lower inclined surfaces; a reciprocating plunger; a support for an article between said wrapper folding channel and said plunger; means whereby paste can be applied to approximately all of one side of a 65 wrapper, means whereby said paste coated wrapper can be moved to rest between said wrapper folding channel and said article, in such a manner that the paste coated side of said wrapper faces toward said article; and means for actuating said plunger whereby forward movement thereof forces said article against said paste coated side of the wrapper, further forward movement of said plunger causing said article and wrapper to be forced into said wrapper folding channel, whereby said upper and lower plates and inwardly extending side projections cause portions of said paste coated side of the wrapper to be folded against the top 80 and bottom and against the sides of the article, said wrapper having upper and lower unfolded side flaps, portions of the paste coated sides of said flaps being partially folded toward other portions of the paste coated sides of said flaps, the inclined surfaces on said inwardly extending arms, during forward movement of the article and wrapper causing said partial folds to be forced against said upper and lower plates, whereby said paste coated sides of the folded flaps are pressed together, substantially as described.

11. A wrapping machine comprising a wrapper folding channel having upper and lower plates and inwardly extending side projections; auxiliary inwardly extending side projections provided with upper and lower inclined surfaces; arms extending inward from the sides of said channel, said arms extending nearer to said upper and lower plates than do said inwardly extending side projections, and said arms having upper and lower inclined surfaces; a reciprocating plunger; slides extending into said channel parallel to said inwardly extending side projections, said slides having reciprocating movements parallel to those of said plunger, and said slides being provided with upper and lower vertically swinging folders and springs normally swinging said folders toward each other, said folders adapted for engagement with the upper and lower inclined surfaces of said auxiliary inwardly extending side projections; a support for an article between said wrapper folding channel and said plunger; means whereby paste can be applied to approximately all of one side of a wrapper; means whereby said paste coated wrapper can be moved to rest be- 130

tween said wrapper folding channel and said article in such a manner that the paste coated side of said wrapper faces toward said article; means for actuating said 5 plunger whereby forward movement thereof forces said article against said paste coated side of the wrapper, further forward movement of said plunger causing said article and wrapper to be forced into said wrapper 10 folding channel, whereby said upper and lower plates and inwardly extending side projections cause portions of said paste coated side of the wrapper to be folded against the top and bottom and against the 15 sides of the article, said folded wrapper having upper and lower unfolded flaps extending beyond the rear and the sides of the article, portions of said paste coated side flaps being partially folded upon themselves, 20 the inclined surfaces on said inwardly extending arms, during forward movement of the article and wrapper causing said partial folds to be forced against said upper and lower plates, whereby the paste coated sides 25 of the folded flaps are pressed together; in combination with upper and lower movable folders adapted to fold said upper and lower unfolded flaps, and to press the paste coated sides thereof against said article; one of 30 said movable folders being provided with laterally swinging folders, at times in range with said reciprocating slides; certain unfolded portions of said folded flaps being at such times in range with said laterally 35 swinging folders; and means for actuating said slides whereby forward movement thereof causes said laterally swinging folders to fold said unfolded portions of said folded flaps, said laterally swinging folders 40 arranged to cause said unfolded portions of said folded flaps to be pressed against said partially wrapped article, and also to cause portions of said paste coated side flaps to be partially folded upon themselves, and toward 45 said upper and lower plates, said forward movement of said slides also causing the upper and lower swinging folders thereon to engage the upper and lower inclined surfaces of said auxiliary inwardly extending 50 side projections, thereby causing said folders to swing against said partial folds, thereby forcing said folds against said upper and lower plates, whereby said paste coated sides of the folded flaps are pressed together. 55 12. A wrapping machine comprising a wrapper folding channel having upper and lower plates and inwardly extending side projections; auxiliary inwardly extending side projections provided with upper and lower inclined surfaces, a reciprocating plunger; slides extending into said channel parallel to said inwardly extending side projections, said slides having reciprocating movements parallel to those of said plunger, and said slides being provided with 60 65 upper and lower vertically swinging folders and springs normally swinging said folders toward each other, said folders adapted for engagement with said upper and lower inclined surfaces; a support for an article between said wrapper folding channel and said plunger; means whereby paste can be applied to approximately all of one side of a wrapper; means whereby said paste coated wrapper can be moved to rest between said wrapper folding channel and said article in such a manner that the paste coated side of said wrapper faces toward said article; means for actuating said plunger whereby forward movement thereof forces said article against said paste coated side of the wrapper, further forward movement of said plunger causing said article and wrapper to be forced into said wrapper folding channel whereby portions of said paste coated side of the wrapper are partially folded upon the article, said partially folded wrapper having upper and lower unfolded flaps; in combination with upper and lower movable folders adapted to fold certain of said upper and lower unfolded flaps, and to press the paste coated sides thereof against said article, one of said movable folders being provided with laterally swinging folders at times in range with said reciprocating slides; certain unfolded portions of said folded flaps being at such times in range with said laterally swinging folders; and means for actuating said slides whereby forward movement thereof causes said laterally swinging folders to fold said unfolded portions of said folded flaps, said laterally swinging folders arranged to cause said unfolded portions of said folded flaps to be pressed against said partially wrapped article, and also to cause partial folds of certain of said unfolded flaps between said folders and said upper and lower plates; said forward movement of said slides also causing the upper and lower vertically swinging folders thereon to engage said upper and lower inclined surfaces, thereby causing said folders to swing against said partial folds, thereby forcing said folds against said upper and lower plates, whereby the paste coated sides of said folds are pressed against each other, substantially as described. 70 75 80 85 90 95 100 105 110 115 120 125 130

13. A wrapping machine comprising a channel through which partially wrapped articles are successively moved, a vertically reciprocating plunger above said channel, said plunger having downwardly extending folders, one of said folders being located on each of the two sides of said channel and in range with upper wrapper flaps of a partially wrapped article, and another one of said folders extending transversely to said channel and in range with an upper wrapper flap of a partially wrapped article succeed-

ing the first named partially wrapped article, whereby downward movement of said plunger causes said folders to fold said wrapper flaps downward against said partially wrapped articles; a vertically reciprocating plunger below said channel, said plunger having an upwardly extending folder located on each of two sides of said channel and in range with lower wrapper flaps of the first named partially wrapped article; and vertically swinging arms having an upwardly extending folder extending transversely to said channel and in range with a lower wrapper flap of said succeeding partially wrapped article; said vertically swinging arms being actuated by the last named plunger; upward movement of the last named plunger causing said upwardly extending folders thereof to fold said lower wrapper flaps of the first named partially wrapped article upward against the wrapped article, said upward movement of the last named plunger also causing upward movement of said vertically swinging arms, whereby said upwardly extending folder thereof folds said lower wrapper flap of the succeeding partially wrapped article upward, said vertically swinging arms arranged to cause said upwardly extending plate thereof to press said folded wrapper flap against said succeeding partially wrapped article.

14. A wrapping machine comprising a channel through which partially wrapped articles are successively moved, a vertically reciprocating plunger above said channel, said plunger having downwardly extending swinging arms having rollers journaled at the lower ends thereof, one of said rollers being located on each of two sides of said channel and in range with upper wrapper flaps of a partially wrapped article, and another one of said rollers extending transversely to said channel and in range with an upper wrapper flap of a partially wrapped article succeeding the first named partially wrapped article, whereby downward movement of said plunger causes said rollers to fold said wrapper flaps downward, the swinging arms carrying said rollers being spring pressed to cause said roller to press said folded wrapper flaps against said articles; a vertically reciprocating plunger below said channel, said plunger having upwardly extending swinging arms having rollers journaled at the upper ends thereof, said rollers being located on each of two sides of said channel and in range with lower wrapper flaps of the first named partially wrapped article; and vertically swinging arms having an upwardly extending folder extending transversely to said channel and in range with a lower wrapper flap of said succeeding partially wrapped article, said vertically swinging arms being actuated by the last named plunger; upward movement of the last named plunger causing upward movement of said vertically swinging arms whereby said upwardly extending folder thereof folds said lower wrapper flap of the succeeding partially wrapped article upward, said vertically swinging arms arranged to cause said upwardly extending folder thereof to press said folded wrapper flap against said succeeding partially wrapped article; reciprocating slides to the rear of and in range with said laterally swinging folders at the 130

actuated by the last named plunger, upward movement of the last named plunger causing said rollers to fold said lower wrapper flaps of the first named partially wrapped article upward, the swinging arms carrying 70 said rollers being spring pressed to cause said rollers to press said folded wrapper flaps against the wrapped article, said upward movement of the last named plunger also causing upward movement of said vertically swinging arms whereby said upwardly extending folder thereof folds said lower wrapper flap of the succeeding partially wrapped article upward, said vertically swinging arms arranged to cause said upwardly extending plate thereof to press said folded wrapper flap against said succeeding 80 partially wrapped article.

15. A wrapping machine comprising a channel through which partially wrapped articles are successively moved, a vertically reciprocating plunger above said channel, said plunger having downwardly extending folders, one of said folders being located on each of two sides of said channel and in range with upper wrapper flaps of a partially wrapped article, and another one of said folders extending transversely to said channel and in range with an upper wrapper flap of a partially wrapped article succeeding the first named partially wrapped article, whereby downward movement of said plunger causes said folders to fold said wrapper flaps downward against said articles; a vertically reciprocating plunger below said channel, said plunger having an upwardly extending folder located on each of two sides of said channel and in range with lower wrapper flaps of the first named partially wrapped articles; vertically swinging arms having an upwardly extending folder extending transversely to said channel and in range with a lower wrapper flap of said succeeding partially wrapped article; said upwardly extending folder being 100 provided with laterally swinging folders; said vertically swinging arms being actuated by the last named plunger; upward movement of the last named plunger causing said upwardly extending folders thereof to fold said lower wrapper flaps of the first named partially wrapped article upward against the wrapped article, said upward movement of the last named plunger also causing upward movement of said vertically 110 swinging arms whereby said upwardly extending folder thereof folds said lower wrapper flap of the succeeding partially wrapped article upward, said vertically swinging arms arranged to cause said upwardly extending folder thereof to press said folded wrapper flap against said succeeding partially wrapped article; reciprocating slides to the rear of and in range with said laterally swinging folders at the 120

125

time said upwardly extending folder of said vertically swinging arms is in its uppermost position, certain unfolded portions of said folded flaps of the wrapper of the succeeding partially wrapped article being at such times in range with said laterally swinging folders; and means for actuating said slides whereby forward movement thereof causes said laterally swinging folders to fold said unfolded portions of said flaps of the wrapper of said succeeding partially wrapped article, said laterally swinging folders arranged to cause said flaps to be pressed against said succeeding partially wrapped article.

16. A wrapping machine comprising a channel through which partially wrapped articles are successively moved; in combination with upper and lower movable folders adapted to fold and press certain wrapper flaps against said partially wrapped articles; one of said movable folders being provided with laterally swinging folders; reciprocating slides to the rear of and in range with said laterally swinging folders at the time the movable folder carrying said laterally swinging folders has reached the end of its movement causing said folding and pressing of a wrapper flap against a partially wrapped article, certain unfolded portions of said folded flaps being at such times in range with said laterally swinging folders; and means for actuating said slides whereby forward movement thereof causes said laterally swinging folders to fold said unfolded portions of said folded flaps, said laterally swinging folders arranged to cause said portions of said folded flaps to be pressed against said article.

40. 17. A wrapping machine comprising a channel through which partially wrapped articles are successively moved, the wrapper of each of said partially wrapped articles having upper and lower unfolded flaps, said channel having upper and lower plates and inwardly extending side projections provided with upper and lower inclined surfaces; reciprocating slides extending into said channel parallel to said inwardly extending side projections; said slides being provided with upper and lower vertically swinging folders and springs normally swinging said folders toward each, said folders adapted for engagement with said upper and lower inclined surfaces; in combination with upper and lower movable folders adapted to fold and press said wrapper flaps against said partially wrapped articles; one of said movable folders being provided with laterally swinging folders at times in range with said reciprocating slides, certain unfolded portions of said folded flaps being at such times in range with said laterally swinging folders; and means for actuating said slides whereby for-

ward movement thereof causes said laterally swinging folders to fold said unfolded portions of said folded flaps, said laterally swinging folders arranged to cause said unfolded portions of said folded flaps to be pressed against said partially wrapped article, and also to cause partial folds of certain of said unfolded flaps between said folders and said upper and lower plates; said forward movement of said slides also causing the upper and lower vertically swinging folders thereon to engage said upper and lower inclined surfaces, thereby causing said folders to swing against said partial folds, whereby said partial folds are forced against said upper and lower plates.

18. A wrapping machine comprising a channel having upper and lower plates; reciprocating slides extending inward from the sides of said channel; auxiliary reciprocating slides actuated by the first named reciprocating slides at the end of each forward and return movement thereof, said auxiliary slides extending into said channel parallel to the first named reciprocating slides, said auxiliary slides extending near to said upper and lower plates and being provided with upper and lower inclined surfaces; means whereby an article and a wrapper can be moved into said channel, whereby the wrapper is folded upon the article in such a manner that upper and lower unfolded flaps overhang the rear and the sides of the article, and that said overhanging side flaps are partially folded toward said upper and lower plates, said partial folds during the forward movement thereof taking against said upper and lower inclined surfaces of said auxiliary slides, whereby said folds are pressed against said upper and lower plates; in combination with upper and lower movable folders adapted to fold said upper and lower flaps overhanging the rear of the article, one of said movable folders being provided with laterally swinging folders at times in range with said reciprocating slides, certain unfolded portions of said folded rear flaps being at such times in range with said laterally swinging folders; and means for actuating the first named slides whereby forward movement thereof causes forward movement of said auxiliary slides, said forward movement of the first named slides also causing said laterally swinging folders to fold said unfolded portions of said folded rear flaps toward the partially wrapped article, said laterally swinging folders also causing partial folds of said flaps overhanging the sides of the article, and between said folders and said upper and lower plates; return movement of the first named slides permitting return movement of said laterally swinging folders and also causing return movement of said auxiliary slides, thereby causing the

upper and lower inclined surfaces thereof to take against said partial folds of said flaps overhanging the sides of the article, whereby said folds are pressed against said upper and lower plates.

5 19. A wrapping machine comprising a channel having upper and lower plates, and stationary inwardly extending side projections provided with upper and lower inclined surfaces; reciprocating slides extending into said channel parallel to said inwardly extending side projections; said slides being provided with upper and lower vertically swinging folders and springs normally swinging said folders toward each other, said folders adapted for engagement with said upper and lower inclined surfaces; auxiliary reciprocating slides actuated by the first named reciprocating slides 10 at the end of each forward and return movement thereof, said auxiliary slides extending into said channel parallel to the first named inwardly extending side projection, said auxiliary slides extending near to said upper and lower plates and being provided with upper and lower inclined surfaces; means whereby an article and a wrapper can be moved into said channel, whereby the wrapper is folded upon the article in 15 such a manner that upper and lower unfolded flaps overhang the rear and the sides of the article, and that said overhanging side flaps are partially folded toward said upper and lower plates; said partial folds 20 during the forward movement thereof taking against said upper and lower inclined surfaces of said auxiliary slides, whereby said folds are pressed against said upper and lower plates; in combination with upper and lower movable folders adapted to 25 fold said upper and lower flaps overhanging the rear of the article, one of said movable folders being provided with laterally swinging folders at times in range with the first named reciprocating slides, certain unfolded portions of said folded rear flaps being at such times in range with said laterally swinging folders; and means for actuating the first named slides, whereby forward movement thereof causes forward movement of said auxiliary slides, said forward movement of the first named slides also causing said laterally swinging folders to fold said unfolded portions of said folded rear flaps toward the partially wrapped article, said laterally swinging folders also causing partial folds of said flaps overhanging the sides of the article, and between said folders and said upper and lower plates; 30 said forward movement of the first named slides also causing the upper and lower vertically swinging folders thereon to engage said upper and lower inclined surfaces on said stationary inwardly extending side projection, thereby causing said folders to

swing against said partial folds of said upper and lower flaps overhanging the sides of the article, whereby said folds are pressed against said upper and lower plates; return movement of the first named slides permitting return movement of said vertically swinging folders and said laterally swinging folders, and also causing return movement of said auxiliary slides, thereby causing the upper and lower inclined surfaces thereon to take against said partial folds of the wrapper, whereby said partial folds are pressed against said upper and lower plates.

70 20. A wrapping machine comprising a wrapper folding channel having upper and lower plates and inwardly extending side projections; reciprocating slides extending into said channel parallel to said inwardly extending side projections; auxiliary reciprocating slides actuated by the first 80 named slides at the end of each forward and return movement thereof, said auxiliary slides extending into said channel parallel to the first named inwardly extending side projections, said auxiliary slides extending 85 nearer to said upper and lower plates than do the first named inwardly extending side projections; means whereby an article and a wrapper can be forced into said channel, whereby said upper and lower plates cause 90 the wrapper to be folded upon the article in such a manner that upper and lower unfolded flaps overhang the rear and sides of the article, said inwardly extending side projections causing the wrapper to be folded 95 against the sides of the article, and also causing certain partial folds of certain of said upper and lower unfolded side flaps between said inwardly extending side projections and said upper and lower plates; 100 said partial folds of the wrapper during forward movement thereof taking against said upper and lower inclined surfaces of said auxiliary slides, whereby said folds are pressed against said upper and lower plates; 105 in combination with upper and lower movable folders adapted to fold said upper and lower flaps overhanging the rear of the article, one of said movable folders being provided with laterally swinging folders at 110 times in range with the first named reciprocating slides, certain unfolded portions of said folded rear flaps being at such times in range with said laterally swinging folders; and means for actuating the first named 115 slides, whereby forward movement thereof causes forward movement of said auxiliary slides, said forward movement of the first named slides also causing said laterally swinging folders to fold said unfolded portions of said folded rear flaps toward the partially wrapped article, said laterally swinging folders arranged to cause said unfolded portions of said folded flaps to be 120 pressed against said partially wrapped ar- 130

ticle; return movement of the first named slides permitting return movement of said laterally swinging folders, and also causing return movement of said auxiliary slides, thereby causing the upper and lower inclined surfaces thereof to take against said partial folds of the wrapper, whereby said partial folds are pressed against said upper and lower plates.

Signed at New York city, in the county of New York and State of New York, this 6th day of August, A. D. 1914.
